WO 2012134983 A2 10/2012

Primary Examiner — Lilyana Bekic

Assistant Examiner — Sharon S Oum

(57) **CLAIM**

The ornamental design for a fan head, as shown and described.

DESCRIPTION

FIG. 1 is a right, front, top perspective view of a fan head in accordance with the present invention;

FIG. 2 is a front elevation view thereof;

FIG. 3 is a top plan view thereof;

FIG. 4 is a back elevation view thereof;

FIG. 5 is a bottom plan view thereof; and,

FIG. 6 is a left elevation view thereof. The right and left sides are mirror images.

The broken lines illustrate portions of the fan head and the stand environment. None of the broken lines form part of the claimed design.

1 Claim, 6 Drawing Sheets(56)
